UNITED STATES PATENT OFFICE

2,542,889

HEAT RESPONSIVE ELECTRIC SWITCH

Paul Baertl, Zurich, Switzerland

Application November 20, 1948, Serial No. 61,165
In Switzerland December 22, 1947

4 Claims. (Cl. 200—142)

1

This invention relates to an electrical contact maker applicable in devices for the disclosure of temperature raising, comprising a movable contact member submitted to the force of a spring and a fixed contact member.

According to the invention, between such contact members a replaceable insulating part is provided consisting of a nonconductive material, capable of melting at temperature raising.

This insulating part may consist of paraffin, stearin, wax or of a mixture of two or three of these substances. Preferably this fusible material is mounted on a support consisting of conductive material and may be inserted or arranged between the contact members. The contact maker may be contained in a tube or casting provided with connecting terminals or may be disposed on a part in form of a cane or a rod, particularly if the device is destined for haystacks, in which case the cane or rod is put into the hay. Preferably the contact maker is connected to a source of electric current and to optic or acoustic signal means. If the contact maker comprises several contacts, these contacts may be arranged in series or in parallel.

The device functions as follows:

By attaining a predetermined temperature, in a haystack for instance the insulating part melts, permitting the two contact members to make contact and therefore to close an electric circuit. If the insulating part consists of a layer of fusible material coating a metallic support, which is particularly convenient if the insulating part is to be easily replaced, the support forms a bridge between the two connecting terminals of the circuit. Preferably one of the connecting terminals is mounted in a suitable manner to be removed, in order to facilitate the replacement of the insulating part.

The accompanying drawing shows by way of example one form of a contact maker of the present invention, which is not limited to the exact construction shown.

In the drawing,

Fig. 1 is a sectional view of a connecting terminal of the contact maker,

Fig. 2 is an axial section of a part of the device with a connecting nipple.

Fig. 3 is an enlarged cross section of one of the parts shown in Figs. 1 or 2.

Referring to the drawings the device comprises parts or elements of Fig. 1 and one element of Fig. 2 for special purposes.

The element consists of a tube 1, which, in the case of Fig. 1, is provided with a point 2.

2

Other elements (Fig. 1) are provided on both ends with threads 3 on the outer side, permitting the connection of a desired number of such elements by means of nipples 4. Two strips 5 of semi-circular cross section are arranged within the tubes 1. The outer surface of such strips is coated with a layer 6 of insulating material having a predetermined melting point. In the center of the tubes 1 a metal rod 7 is disposed, which

10 rod is slotted over a part of its length, forming two outwardly curved halves 8, abutting like springs against the strips 5 and pressing the insulating layer 6 against the inner surface of tube 1.

15 The ends 9 of the rods 7 are fixed in a bore 10 of a base 11 and sleeve 12 of insulating material, pressed into the ends of the tubes 1. The ends 13 of the rods 7 protrude from the sleeves 12 to make electric contact when two elements are connected by a nipple 4.

Thus the tubes 1 of the elements are connected electrically by means of the nipples 4 and the rods 7 make contact at the contacting ends 13.

To lead voltage to the tubes 1 and rods 7 respectively a nipple 14 is screwed on to the thread 3 of the first element. A central portion 15 of insulating material is provided on this nipple 14. Within this portion 15 a contact socket 16 is disposed for receiving a plug. A projection 17 of the socket 16 makes contact with the front side 18 of the end 9 of a rod 7.

A source of current 19 delivers the voltage. The circuit comprises an acoustic signal 20 and is completed by a lead 21, a plug 22 and a plug 23 to be inserted into a bore 24 of the nipple 14.

In place of sockets and plugs, screws and nuts may be provided on the nipple 14 to connect the source of current 19 with the contact maker constituted by the elements described.

40 Such devices are permanently located in rooms in which raising of temperature above a predetermined value must be controlled to lessen fire hazard.

To control the temperature in a haystack or a similar material the device provided with a tapered element (Fig. 1) is inserted into such stack or material.

In practice the elements preferably have a length of 1 to 2 metres.

50 What I claim is:

1. A raised temperature responsive electric circuit control device, comprising a tubular first conductor, a second conductor disposed within said first conductor having a spring-like portion tending toward said first conductor, a pair of

replaceable contact elements disposed intermediate said first and said second conductors for substantially sheathing said second conductor, non-conducting material possessing a given melting characteristic on the outer surfaces of said replaceable contact elements, and means forming a connection for an electric current supply circuit from said first to said second conductor.

2. A device according to claim 1, wherein said material comprises a paraffin-like substance.

3. A raised temperature responsive electric circuit control device as claimed in claim 1, wherein said second conductor has at one end thereof an outwardly projecting longitudinal extension, and further including means forming an operative connection for a second device.

4. A device as claimed in claim 3, further including at least a second device placed end to end in relation to said first device having an ex-

tending second conductor making contact with the extended end of the second conductor of said first device, said connection forming means connecting said respective first conductors.
